TUMBLER LOCK

John C. Busche, Highland Park, Mich.

Application April 13, 1938, Serial No. 201,794

1 Claim. (Cl. 70—364)

The present invention relates to tumbler locks and more especially to the locking cylinders therefor.

Among the objects of the invention is to simplify the construction of such devices.

Another object is a device of this character which provides safe locking without the use of springs.

Another object is a lock barrel or plug which permits the use of a greater number of tumblers in a barrel of a given size and therefore a wider variation in the tumbler combinations.

Still other objects and advantages will be apparent from the following description and the accompanying drawing in which

Figure 1 is a central longitudinal section through the lock barrel in the plane of the key.

Figure 2 is a perspective view of the barrel with parts broken away.

Figures 3 to 6 are perspective views of details of the construction.

Figure 7 is a section on line 7—7 of Figure 1, and

Figure 8 is a section on line 8—8 of Figure 1.

In the drawing, the lock is indicated as consisting of a series of tumblers 10 slidably carried in a cage 11, which with the tumblers properly aligned is rotatably enclosed in a slotted barrel 12 and this in turn is enclosed by the outer housing 15, the several parts being held together by a pin or key 16.

Of the several parts, the tumblers 10 may be of channel form as shown (in which case the sides of the channel act as spacers) or if more tumblers are to be used, the channels may be more shallow or the tumblers may be flat. In any case each will have a suitable slot 10a to permit the passage of a key 20 which cooperates with the ends of the slots.

The cage 11 is preferably produced from a disc 11a with a U-shaped member 11b fixed thereto and having one of its legs 11c extending through the disc 11a provided with shoulders 11d near its end. At the end of the cage 11 opposite disc 11a a suitable key hole 11e will be provided and the disc 11a will be slotted centrally at 11g, this slot being shaped to fit and locate the end of key 20 as shown in Figure 1.

The slotted barrel 12 is provided as shown with diametrically located slot 12a into which the ends of tumblers 10 project to prevent rotation of the cage, and is also provided at its closed end with a central opening 12b and with openings 12c in its sides for the passage of pin 16.

In addition to the parts described, there is also

the piece 25 shown in Figure 4, which consists of a disc 25a having a squared post 25b fixed axially thereto, the disc being provided with a slot 25c.

This member 25 with its squared post fits in the end of member 12 with the post 25b extended through opening 12b and is rotated by the cage 11 through the action of part 11c, this fitting in slot 25c.

The key 20 is, as shown, provided with a series of cams on each edge, those on one edge being located opposite the spaces between cams on the other edge, there being as many cams and opposite spaces as there are tumblers. And, each tumbler slot 10a is only slightly longer than the width of the key at any part of its length.

Further, the key end is so shaped as to fit snugly the slot 11g in cage 11, and it is of course obvious that the cams may be of different heights to agree with differing locations of tumbler slots 10a.

When the parts are assembled as indicated, insertion of the key 20 will of course align the tumblers 10 within cage 11 and out of slots 12a, permitting the cage to turn and with it rotate member 25, this rotation being limited in either direction by the projection 11c striking pin 16.

As the key is inserted and progresses to its destination, namely, its end point at which the key ceases its forward motion, the tumblers are actuated reciprocally until the key ceases its forward motion, at which time each and every tumbler has found its correct position, namely that of alignment which is constituted by the tumblers having their ends in parallel lines, permitting the cylinder to rotate and thus either lock or unlock the mechanism.

When the key is withdrawn, provided the cage 11 is in proper position, the tumblers 10 will be projected into the slots 12a and lock the cage and thereby the post 25b. Some of the tumblers will of course be moved in one direction and some in the other.

Now having described the invention and the preferred embodiment, it is to be understood that said invention is to be limited, not to the specific details herein set forth, but only by the scope of the claim which follows:

What I claim is:

A lock barrel for tumbler locks comprising a cylindrical housing open at one end and closed at the other and having a key admitting opening at the closed end, a second cylindrical member having an open end and provided with a central opening in its closed end telescoped into the housing with its closed end outermost, said second

member being also provided with diametrically located slots, a cage rotatable within said second member and carrying a plurality of slidable tumblers adapted to project into said slots to prevent cage rotation, a tongue projecting from one end of said cage, bolt operating means projecting from the opening in the ends of said second member and actuatable by the projecting

tongue of said cage, each of said tumblers being slotted for the reception of a key whereby said tumblers may be properly aligned and withdrawn from the diametrical slots and said cage rotated, and means for fixing together the housing and second member, said fixing means also serving to limit cage rotation. 5

JOHN C. BUSCHE.
